FEELER-MOTION FOR LOOMS.

1,225,120.

Specification of Letters Patent.

Patented May 8, 1917.

Application filed January 22, 1916. Serial No. 73,716.

To all whom it may concern:

Be it known that I, THOMAS FERGUSON, a subject of King George V of Great Britain, residing at Lowell, county of Middlesex, and State of Massachusetts, have invented an Improvement in Feeler-Motions for Looms, of which the following description, in connection with the accompanying drawings, is a specification, like characters on the drawings representing like parts.

The invention to be hereinafter described relates to feeler motions for looms through the agency of which the loom may be stopped or the filling replenished when that in the shuttle has become substantially though not fully exhausted.

Various forms of feeler mechanisms have heretofore been proposed, some of which depend for their effective action upon measurement of the thickness of the filling on the carrier or bobbin in the shuttle, others upon movement of the feeler in a direction longitudinally of the shuttle when the filling has reached a condition of substantial exhaustion. Feeler mechanisms to be practically efficient, must be very sensitive because on the one hand, when the substantial exhaustion of the filling is reached and only sufficient remains in the shuttle to make one, two, or more picks, as the case may be, the feeler must be sufficiently sensitive to this condition to set in operation a train of mechanism to effect either replenishment of the filling or loom stoppage, and on the other hand, must effectively prevent the operation of such train of mechanism when sufficient filling remains in the shuttle for weaving purposes.

An important feature of the present invention, therefore, consists in a feeler motion wherein the feeler shall be sensitive to the condition of substantial exhaustion of the filling and thereupon set in operation a train of mechanism to change the condition of the loom, as by causing replenishment of the filling or loom stoppage, and at the same time will be equally sensitive to the presence of a working supply of filling in the shuttle to prevent operation of such train of mechanism so long as such working supply is present.

This feature of the invention is carried into practical effect by providing the feeler motion with a rotatable feeler having a portion adapted to engage the filling in the

shuttle as the lay makes its detecting beat, and to be moved forward by such beatup movement of the lay, the engaging portion of the feeler being such that when a working supply of filling is present, such feeler shall be prevented from rotating about its longitudinal axis as it is moved forward by the mass of filling in the shuttle, but upon substantial exhaustion of the filling that such rotative movement of the feeler shall be permitted and thereupon set into operation a train of mechanism to change the condition of the loom either by filling replenishment or loom stoppage.

Another feature of the present invention consists in a feeler motion having a rotatable or rocking feeler and an arm associated therewith, and which feeler will be prevented from such rotative or rocking movement on the detecting beat of the lay by engagement with the filling until the latter has reached a desired degree of exhaustion, and thereupon may be turned or rocked to effect filling replenishment or loom stoppage, as the case may be. In carrying into effect this feature of the invention, the feeler is mounted for rotative or rocking movement about its longitudinal axis or about an axis extending toward the rear of the loom, and is normally under the influence of means such as a spring, tending to impart to such feeler its rotative or rocking movement as the feeler is moved forward on the detecting beat of the lay.

Other features of the invention will hereinafter be described in connection with the illustrated form thereof, and such features, together with the combinations of elements peculiar to the organization, will be subsequently defined by the claims.

In the drawings:—

Figure 1 is a plan view showing sufficient portions of the loom frame, the lay and its associated parts, and the feeler to make clear the characteristics of the invention;

Fig. 2 is an enlarged detail side view of the rotative or rocking feeler with parts broken away, showing the filling-engaging part of the feeler in contact with a working supply of filling on the bobbin or carrier in the shuttle during the forward movement of the lay.

Fig. 3 is an enlarged end view of the feeler looking in the direction of the arrow, Fig. 1;

Fig. 4 is a side elevation of the feeler and its associated parts similar to that of Fig. 2, but showing the action of the feeler on its frontward movement when the filling is substantially exhausted; and

Fig. 5 is a view in slightly modified form, of the feeler.

The present invention is especially adapted for application to an automatic loom wherein filling replenishment is made effective to provide a fresh supply of filling when that in the active shuttle has become nearly or substantially exhausted; but it may, obviously, also be employed in connection with some other train of mechanism. In the illustrated form of the invention, the loom frame may be and is of any usual or desired character and secured to the breast beam 1 is the transverse or change shaft 2. This transverse or change shaft 2 is common in filling replenishing looms, and may be connected as usual to suitable means for initiating filling replenishment when said shaft is rocked, all as will be readily understood by those skilled in the art. Secured to the transverse shaft 2 and extending upward therefrom, is the usual arm 3 having pivotally connected thereto the arm 4 which may for identification be termed a latch or actuating latch because by frontward movement thereof the transverse or change shaft 2 is rocked in opposition to the usual spring means for holding the transverse shaft 2 and its connected parts in inoperative position. Rearward of the actuating latch 4 is the actuator 5 which, as usual, may be either the weft hammer or a part connected thereto, and adapted to engage the end portion of the actuating latch 4 on frontward movement of the actuator to cause said actuating latch to be moved frontward and thereby rock the transverse or change shaft 2 when the end of the latch is permitted to be positioned for engagement by the actuator. Pivoted at 6 is the knock-off lever 7, one end of which is adapted to bear against a shipper 8 and to effect disengagement of said shipper from its holding notch as usual when said knock-off lever 7 is turned upon its pivotal mounting 6 in a clockwise direction, viewing Fig. 1.

Pivoted on the bracket 9 at 10 is the transmitter 11 by which the position of the actuating latch 4 relative to the actuator 5 may be controlled. In the illustrated form of the invention the transmitter 10 is normally under the influence of a light spring 12 tending to depress the latch-engaging end of the transmitter and to permit the end of such transmitter to be normally below the path of movement of the actuator 5, the construction being such that should the transmitter be turned in a direction against the tension of the light spring 12, 65 that is in a direction to lift its latch-engag-

ing end, said latch will be positioned for engagement by the actuator 5 as the latter moves frontward. The transverse or change shaft, the latch 4 and actuator 5 may be substantially the same as that disclosed in the patent to Wood and Northrop, No. 843,249, dated February 5, 1907. The loom frame 13, only part of which is indicated in Fig. 1, sustains the usual lay 14 provided with the usual shuttle-boxes for the reception of the shuttle 15 in which is carried the usual filling carrier or bobbin 16 on which the filling 17 is wound. The bobbin 16 may be of any appropriate character and as shown it has the usual rings 18 for engagement with the holding jaws in the shuttle and the shuttle itself is as usual, provided with an opening in its lower wall through which a bobbin may be ejected by the filling replenishing mechanism when a new supply of filling is transferred to the shuttle. The shuttle-box may be likewise provided with usual opening 19 in its front wall adapted to register with a corresponding opening 20 in the side wall of the shuttle, the construction being such that when the shuttle 15 is in the box opposite the feeler, the filling engaging portion of the feeler may enter the shuttle and feel for the filling as the lay makes its de-teeting beat.

Mounted upon a suitable bracket 21, Fig. 2, is an appropriate stand 22 in which is rotatably mounted the feeler 23. The stand 22 may be of any appropriate character and as shown comprises a lower plate 24 and a top plate 25 appropriately secured in cooperative relation by suitable means such as the screws 26, Fig. 1, and in order that the stand 22 may be adjusted relative to the supporting bracket 21, the flanged portion of the base and cover plates 24 and 25 may be provided with a slot 27 through which extend the securing means such as the bolts 28, Fig. 1, for holding the stand 22 and perforce, the feeler in appropriate position.

The stand 22 is provided with suitable bearing portions 29 at its front and rear ends for the rotatable feeler 23, which is preferably formed circular in cross section, the construction being such that the feeler 23 may slide toward and from the front of the loom in such bearing portions 29 and be rocked or rotated therein.

The feeler 23 is normally under the influence of means for projecting it toward the rear of the loom, such means in the present instance, being shown as a spring 30 surrounding the feeler 23 within the stand 22 and a stop pin 31 is provided for limiting the rearward movement of the feeler under the impulse of the spring, the construction being such that the feeler 23 will be normally held in rearward position by the spring 30.

As hereinbefore noted, an important fea-

ture of the present invention consists in a rotatable or rocking feeler, and in order to effect such rotative or rocking movement of the feeler, the spring 30 which normally projects the feeler rearward also tends normally to turn or rock the feeler upon its longitudinal axis. To this end one portion of the spring as at 32 is secured to the feeler stand 22, Fig. 2, and the other end 33 of the spring 30 is connected to the feeler, the construction being such that the spring 30 normally exerts a turning or rocking tendency to the feeler. It may be desirable at times to vary the rocking or turning tendency of the spring 30 upon the feeler 23, and to this end one portion of the spring 30 as at 33 is connected adjustably to the feeler. In the present instance such adjustability of the end 33 of the spring is secured by means of a sleeve 34 to which one end 33 of the spring 30 is secured, the other end of said sleeve being provided with a series of notches 35 adapted to selectively engage a pin 36 extending from the feeler, the construction being such that by forcing the sleeve 34 forward or to the left, Fig. 2, the notched end portion thereof may be disengaged from the pin 36 and turned either to increase or decrease the torsional action of the spring 30, whereupon, by release of the sleeve 34, the appropriate notch will at once be engaged by the pin 36 to hold the parts in adjusted position.

The feeler 23 is provided with a filling engaging portion 37, Figs. 2 and 4, which is so formed and roughened or serrated that when such engaging portion is engaged by a working supply of filling in the shuttle as the lay makes its detecting beat and thereupon moves the feeler 23 forward, the mass of filling in the shuttle will prevent rotative or rocking movement of the feeler 23 about its longitudinal axis responsive to the spring 30, Fig. 2; but when the filling has become substantially exhausted, as in Fig. 4, the end portion 37 of the feeler will no longer be held from turning or rocking movement as the lay makes its detecting beat so that on forward movement of the feeler, the spring 30 by its torsional action will turn the feeler about its longitudinal axis and effect filling replenishment as will presently appear.

It is the purpose of the present invention to utilize the turning or rocking movement of the feeler which is permitted when the filling has become substantially exhausted, to initiate or start in operation a train of mechanism to effect filling replenishment when the shuttle returns to the filling replenishing side of the loom. To this end the feeler 23 has associated therewith, means actuated by its turning or rocking movement as the feeler moves forward to effect filling replenishment. In the present in-

stance such means consists of an arm or finger 38 which is secured to the feeler and which by turning or rocking movement of the feeler as hereinbefore noted, is carried from its normal or full line position, Fig. 3, 70 to the dotted line position. In the illustrated form of the invention the arm or finger 38 is moved downwardly from its full to its dotted line position but it will be obvious of course that this will depend entirely upon the direction of torsional impulse of the feeler turning or rocking means which, in the present instance of the invention, is the spring 30 and which is illustrated as tending to turn the feeler in a 80 direction to depress the arm or finger 38.

The transmitter 11 is provided with a part 39, Figs. 1 and 3, adapted to be engaged and moved by the arm or finger 38 when the latter is moved by the turning or rocking movement of the feeler. In the present instance of the invention the part 39 is formed as a ledge or table as indicated in Fig. 1 positioned beneath the end of the arm or finger 38, the construction being 90 such that when the feeler is turned as hereinbefore noted, the finger or arm 38 will be depressed and by engagement with the part 39 actuate the transmitter 11 to position the actuating latch 4 in the path of 95 the actuator 5 which thereupon, by its forward movement, will rock the transverse or change shaft 2 and initiate filling replenishment.

In order that the feeler 23 may be turned 100 or rocked at the critical time as the lay makes its detecting beat when filling is substantially exhausted, and yet be held from such rocking movement when the feeler is in its rearward position, means are provided to permit such rocking movement only when the feeler is moved forward and to restore or rock the feeler to its original position when the feeler is in its rearward position. In the present instance of 110 the invention, the stand 23 is provided with the incline or cam portion 40, Figs. 2 and 4, leading from a position or horizontal edge 41 and adapted to be engaged by the arm or finger 38, the construction being such 115 that when the feeler is in its rearward position as indicated in Fig. 2, the arm or finger 38 will rest upon the edge 41 of the stand 22 and hold the feeler from turning or 120 rocking movement responsive to its actuating means or spring 30; but when the feeler is moved forward on the detecting beat of the lay, the finger or arm 38 will move with it and if a working supply of filling is present in the shuttle as indicated 125 in Fig. 2, the engaging portion 37 of the feeler will maintain the feeler from turning or rocking movement responsive to the spring 30, as the feeler moves to its front position; but should the filling have become 130

substantially exhausted, as indicated in Fig. 4, the feeler will no longer be held from turning or rocking movement and the finger or arm 38 will move down the incline or cam portion 40 as the feeler moves forward, thereby actuating the transmitter and initiating filling replenishment. When, on backward movement of the lay, the feeler moves rearwardly again, the finger or arm 38 will move up the incline or cam 40 under the expansive action of the spring 30, and rock the feeler in opposition to the torsional action of the spring 30 and restore it to its original or feeling position, as indicated in Fig. 2.

A rotatable or rocking feeler constructed in accordance with the present invention is extremely sensitive to either the presence or absence of a working supply of filling in the shuttle, and is readily adjustable to the conditions of use by simple and adjustable variation of the action of the spring 30.

While the preferred form of the invention is shown as having the filling-engaging portion of the feeler formed generally circular in character, it is to be understood that such end portion of the feeler may be of any appropriate form which, by engagement with a working mass of filling, will prevent rotative movement of the feeler about its longitudinal axis under the demands of its turning or rocking spring, and yet will permit such rotative or rocking movement when the mass of filling has been depleted to substantial exhaustion.

In Fig. 5 is represented a slightly-modified form of the feeler wherein the end portion of the feeler is turned from axial alignment with the main portion thereof, as at 42, and in this figure also, the feeling end portion of the feeler at 43 is flattened, but in this modification, as in the preferred form of the invention, the turning or rocking movement of the feeler at the critical moment on the detecting beat is the agency whereby filling replenishment or other change in the loom condition is made effective, as described for the preferred form of the invention.

What is claimed is:—

50 1. In a feeler motion for looms, the combination of a feeler having a single filling engaging portion, a torsional spring normally acting to rotate the feeler and prevented from effecting such rotation on a detecting beat by the filling in the shuttle until substantial exhaustion thereof, means for preventing rotative movement of the feeler when not engaged by the filling or carrier in the shuttle, and means for initiating replenishment when the torsional action of the spring effects rotative movement of the feeler.

2. In a feeler motion for looms, the combination of a feeler, a spring normally act-

ing to rotate the feeler, a finger connected to the feeler, a fixed cam having a portion for engaging the finger when the feeler is in rear position to prevent rotation of the feeler under the normal action of said spring, and a fixed inclined portion to permit the spring to rotate the feeler when the filling is substantially exhausted on a detecting beat.

3. In a feeler motion for looms, the combination of a rotatable feeler, a finger connected to the feeler, a fixed stop on which the finger normally rests when the feeler is in rear position to prevent rotation of the feeler, and a spring normally acting to rotate the feeler when the finger is removed from the stop on a detecting beat and the filling is substantially exhausted.

4. In a feeler motion for looms, the combination of a feeler having a filling engaging portion, a finger extending from the feeler, a fixed stop for said finger when the feeler is in rear position, and a spring normally acting torsionally upon the feeler and rotating the same when the finger is removed from the stop on a detecting beat and the filling is substantially exhausted.

5. In a feeler motion for looms, a feeler, a feeler stand having a stop, a finger connected to the feeler and normally resting on the stop when the feeler is in rear position, and a spring for rotating the feeler when the finger is removed from the stop by the forward movement of the lay and the filling is substantially exhausted.

6. In a feeler motion for looms, the combination of a feeler stand having a fixed inclined portion, a feeler mounted for rotative movement in the stand, a spring acting directly on the feeler to turn it about its longitudinal axis, a finger extending from the feeler and resting upon the feeler stand at the top of the inclined portion when the feeler is in rear position and adapted to move along the fixed inclined portion of the stand in response to the spring when the feeler is moved forward on a detecting beat and the filling is substantially exhausted.

7. In a feeler motion for looms, the combination of a feeler stand having a fixed inclined portion, a feeler mounted for rotative movement in the stand, a spring acting directly on the feeler to turn it about its longitudinal axis, a finger extending from the feeler and resting upon the feeler stand at the top of the inclined portion when the feeler is in rear position and adapted to move along the fixed inclined portion of the stand in response to the spring when the feeler is moved forward on a detecting beat and the filling is substantially exhausted, and means rendered effective by the movement of the finger over the fixed

inclined portion of the stand to initiate filling replenishment.

8. In a feeler motion for looms, the combination of a feeler to feel for the filling in the shuttle as the lay beats up, a torsional spring having one end fixed and the other secured to the feeler, said spring normally tending to rock the feeler about its longitudinal axis and prevented from effecting such rocking movement by engagement of the feeler with the wound mass of filling until the filling is substantially exhausted and thereupon effecting such rocking movement, and means rendered effective by such rocking movement of the feeler for replenishing the filling.

9. In a feeler motion for looms, the combination of a feeler to feel for the filling in the shuttle as the lay beats up, a spring tending to rock the feeler about its longitudinal axis and prevented from effecting such rocking movement by engagement of the feeler with the wound mass of filling until the filling is substantially exhausted and thereupon effecting such rocking movement, means for adjusting the rocking tendency of the spring, and means rendered effective by such rocking movement of the feeler for replenishing the filling.

10. In a feeler motion for looms, a feeler to feel for the filling in the shuttle and be moved frontward by the wound mass of filling as the lay beats up, means normally tending to rock the feeler about its longitudinal axis as it is moved frontward and prevented from effecting such rocking movement by engagement of the feeler with the filling until substantial exhaustion, and means independent of the normally acting means for preventing rocking movement of the feeler when the feeler is in its rearward position and becoming ineffective when the feeler is moved frontwardly on a detecting beat.

11. In a feeler motion for looms, the combination of a feeler to feel for the filling in the shuttle as the lay beats up, a torsional spring acting upon the feeler and tending to rotate or rock the feeler about its longitudinal axis and prevented from effecting such rotating or rocking movement by engagement of the feeler with the wound mass of filling until the filling is substantially exhausted and thereupon effecting such rotat-

ing or rocking movement of the feeler for replenishing the filling.

12. A feeler motion for looms, comprising in combination, a feeler mounted for movement longitudinally of and rotative movement about its axis and held from such rotative movement by the mass of filling on the detecting beat-up of the lay until substantial exhaustion of the filling, an arm connected to the feeler, and means for engaging said arm when the feeler is in rear position to prevent rotative movement of the feeler, said arm being freed from said means as the lay beats up to permit the feeler to be rotated or rocked on its longitudinal axis provided the filling is substantially exhausted.

13. A feeler motion for looms, comprising, in combination, a feeler mounted for longitudinal and rotative or rocking movement and held from such rotative or rocking movement on a detecting beat by the filling in the shuttle when a working supply of filling is present, an arm connected to the feeler, means for engaging said arm when the feeler is in rear position to prevent rotative movement of the feeler, said arm being freed from said means by frontward movement of the feeler on a detecting beat to permit the feeler to be rotated or rocked on its axis provided the filling is substantially exhausted, and means coöperating with said feeler when the filling is substantially exhausted to initiate filling replenishment.

14. A feeler motion for looms, comprising, in combination, a feeler mounted for longitudinal and rotative movements and held from such rotatiys movement on a detecting beat of the lay by the filling in the shuttle when a working supply is present, an arm connected to the feeler, a support on which said arm rests when the feeler is in rear position to prevent rotative movement of the feeler and from which it is freed by frontward movement of the feeler to permit rotative movement of the feeler provided the filling is substantially exhausted on a detecting beat, said support having an inclined portion for resetting the feeler as the latter moves to rearward position after a detection of substantial exhaustion of filling, and means coöperating with said arm for initiating replenishment of filling.

In testimony whereof, I have signed my name to this specification.

THOMAS FERGUSON.
